Primary Examiner—Alan P. Douglas*Assistant Examiner*—Robert M. Spear*Attorney, Agent, or Firm*—Stanley M. Miller[57] **CLAIM**

The ornamental design for a plastic lid ashtray for beverage cans, as shown and described.

DESCRIPTION

FIG. 1 is an isometric perspective view of a plastic lid ashtray for beverage cans showing my new design superimposed over a phantom-lined depiction of a standard aluminum beverage can;

FIG. 2 is a top planar view of the invention;

FIG. 3 is a bottom planar view of the invention;

FIG. 4 is a side elevational view of the invention, which, being frusto-conical in configuration, is the same for all four sides of the invention; and,

FIG. 5 is a cross-sectional view taken along the line 5—5 of FIG. 4.

The phantom-lined depiction of a standard aluminum beverage can in FIG. 1 is for illustrative purposes only and forms no part of the claimed design.
